UNITED STATES PATENT OFFICE.

JOSEPH R. BLAINE, OF OAK PARK, ILLINOIS, ASSIGNOR TO MIEHLE PRINTING & MANUFACTURING COMPANY, OF CHICAGO, ILLINOIS, A CORPORATION OF ILLINOIS.

SHEET-GUIDE ADJUSTMENT.

Application filed August 24, 1921. Serial No. 494,994.

To all whom it may concern:

Be it known that I, JOSEPH R. BLAINE, a citizen of the United States, residing at Oak Park, in the county of Cook and State of Illinois, have invented certain new and useful Improvements in a Sheet-Guide Adjustment, of which the following is a specification.

In my Patent No. 1,367,229 I disclose sheet guide adjustable means whereby the gauges during the operation of the press can be adjusted to secure accurate register. The present invention is an improvement upon the arrangement disclosed by said patent.

One object of the invention is to simplify and improve sheet guide adjustment means whereby the action thereof is more direct and positive than heretofore has been the case.

Another object is to provide simple sheet guide adjustment means adapted to meet the various requirements for successful commercial use.

These and other objects are accomplished by means of the arrangement shown on the accompanying sheet of drawings, in which—

Figure 1 is a plan view of a side registering and adjusting mechanism embodying the invention; and

Figure 2 is a view of the same in side elevation with the revolving parts displaced 90° from the position shown in Figure 1.

The various novel features of the invention will be apparent from the following description and drawings, and will be particularly pointed out in the appended claims.

Referring to the figures of the drawings it will be noted that I have disclosed my invention in connection with a printing press including an impression cylinder 10 equipped with the usual grippers 11. Adjacent the cylinder 10 and in parallel relation thereto is a suitably mounted shaft 12 driven at a speed corresponding to that of the shaft of the impression cylinder.

In the patent hereinabove referred to I disclosed both front and side register means, while my present invention relates to side register means and more particularly means for adjusting the same while the press is in operation.

For side registering sheet material there is keyed to the shaft 12 a side gauge arm 13

having an extending boss 14. A collar 15 is loosely mounted upon the boss 14 and held in stationary position by means of an arm 16, one end of which embraces a supporting shaft 17. This collar 15 is provided with a cam 18 in one plane and another cam 19 in a different plane. The side gauge arm 13 carries a side gauge 20 the position of which is adjustable transversely of the press and longitudinally of the shaft 12 by means to be described hereinafter in detail.

As appreciated, if the sheet material were not registered properly it would be very inconvenient to stop the press and then adjust the registering mechanism and then set the press in motion for a trial registration and then possibly stop the press again for further adjustment. By means of the arrangement here shown the side register means may be accurately adjusted while the press is in operation.

In connection with adjusting the position of the side gauge arm 13 and its side gauge member 20, it will be noted that the outer end of the collar 15 is provided with threads 21 and that said collar 15 is held longitudinally to the extending boss 14 of the side gauge arm 13 by any suitable means such as an end plate 22 and screws 23 whereby there is no relative endwise movement between the collar 15 or more particularly with its threaded portion 21 and the gauge arm 13. Threaded onto the threaded portion 21 of the collar 15 is a cap 24, the internal threads 25 of which engage the threaded portion 21 of the collar 15. The opposite end of the cap 24 has an inturned annular portion 26 which is loosely received within a groove 27 of a clamp 28 secured to the rotating shaft 12 by a bolt 29.

Let it be assumed that the side gauge 20 needs adjustment longitudinally of the rotating shaft 12 for correcting registering conditions. To accomplish this adjustment the cap 24 normally stationary, which remains in the same relative position with respect to the clamp 28, may be turned either forward or backward with respect to the threaded portion 21 of the collar 15 whereupon the side gauge arm 13 with its side gauge plate 20 and also the arm 16 and all parts associated therewith may be moved longitudinally with respect to the shaft 12 for correcting side registering conditions.

It will be understood that the side register arm 13 and the parts attached thereto move forwardly with a sheet of paper for front registering the sheet, as described in 5 said patent, and rotates with the shaft 12. The clamp 28 also rotates with the shaft 12, but the remaining parts of the mechanism, including the collar 15 and cap 24, remain stationary. Normally when the side gauge 10 member has been accurately adjusted the adjusting cap 24 is locked in adjusted position by a set screw 30 which is threaded through a bracket 31 formed integrally with the arm 16.

15 In connection with the operation of other parts of the mechanism it will be noted that transversely slidable within the gauge arm 13 there is a shoe 32 carrying a roller 33 which works within an oblique slot 34 of 20 an angle lever 35, 36, the opposite end of which lever has a roller 37 arranged to travel upon the cam 18. The other end of the shoe 32 opposite the roller 33 has pivoted thereto at 38 an arm 39 connected by means 25 of a rod 40 to a link 41 pivoted at 42 to the shoe 32, which link 41 is extended to form a flipper 43. The rod 40 is surrounded by a compression spring 44 the tension of which is adjustable by means of a knurled 30 nut 45. A coiled spring 46 much stiffer than spring 44 holds the stop 47 of the arm 39 against the shoe 32. The angle lever 35, 36 is fulcrumed to the gauge arm 13 upon a pivot 48, and similarly pivoted to said arm 35 at 49 is an angle lever 50, 51, the arm 51 of which is provided with a roller 52 arranged to ride upon the cam 19, while the opposite arm 50 of said lever has an offset portion provided with an inclined face 53 adapted 40 to engage the arm 39 to open and close the flipper 43.

In use the flipper 43 is normally closed, being held in this position by the tension of 45 springs 44 and 46. As the sheet is advanced approximately to the front gauge, not shown, for front registering, the cam roller 52 rides upon the cam 19, opening the flipper 43 to allow the side edge of the sheet to pass and to offer no resistance to the action of the 50 front register. The front register having been obtained the roller 52 rides off the cam 19 closing the flipper 43 upon the sheet 54 at the side thereof. Shortly thereafter the roller 37 rides upon the cam 18, bringing the 55 oblique slot 34 to bear through the roller 33 upon the shoe 32, drawing the sheet 54 to the left, as shown in Figure 1, against a side gauge member 20, the flipper sliding upon the sheet during the further lateral 60 movement of the flipper and shoe after the side registration of the sheet.

At the moment the grippers 11 close on the sheet, the flipper 43 still has hold of the sheet and during the next $1\frac{1}{8}$ " of travel of 65 the cylinder 10 the flipper slips off the sheet

and allows it to pass freely to the impression cylinder. The flipper then remains closed until the next cycle starts. After the sheet is taken the roller 37 rides off of the high part of the cam 18 bringing the shoe 32 back 70 to a starting position.

It is my intention to cover all modifications of the invention falling within the spirit and scope of the following claims.

I claim:

1. In a printing press, the combination of a side gauge for registering sheet material, a shaft by which said side gauge is swung, and means on said shaft and operative coaxially therewith for adjusting the position of said gauge longitudinally of said shaft.

2. In a printing press, the combination of a side gauge for registering sheet material, a shaft by which said gauge is swung, 85 and means on said shaft operative coaxially therewith movable relative to said gauge for adjusting the position of the latter on the shaft longitudinally of said shaft.

3. In a printing press, the combination of a gauge for registering sheet material, a rotary shaft on which said gauge is non-rotatably mounted; and means on said shaft and operative coaxially therewith for adjusting the position of said gauge longitudinally of said shaft for side registering purposes.

4. In a printing press, the combination of a rotary shaft, a side gauge keyed thereto, a collar on said shaft having a threaded portion and locked against lateral movement with respect to said side gauge, and an anchored threaded member cooperating with said threaded collar by means of which said gauge may be adjusted for side registering purposes.

5. In a printing press, the combination of a rotary shaft, a side gauge keyed to said shaft, threaded means on said shaft operative coaxially therewith and locked against relative movement with respect to said side gauge, and means cooperative with said threaded means for adjusting the position of said side gauge longitudinally of said shaft for registering purposes.

6. In a printing press, the combination of a rotary shaft, side register means keyed thereto, and adjustable means on said shaft and operative coaxially therewith for changing the position of said side gauge longitudinally of said shaft for registering purposes.

7. In a printing press, the combination of a rotary shaft, a side gauge keyed thereto and having a cylindrical boss, a collar loosely mounted on said boss, being locked against lateral movement with respect to said side gauge and having a threaded portion, a clamp secured to said shaft and having a grooved portion, and a threaded cap an- 130

chored in the groove of said clamp and co-operating with the threaded collar for adjusting the position of the side gauge for registering purposes.

5 8. In a printing press, the combination of a gauge for registering sheet material, a rotary shaft on which said gauge is mounted, and means on said shaft for adjusting the position of said gauge longitudinally of 10 said shaft for side registering purposes, said means being held against axial movement relative to said shaft but being free to rotate relative thereto.

9. In a printing press, in combination, an

impression cylinder, a shaft having its axis 15 parallel with said cylinder and rotatable simultaneously therewith, a gauge for registering sheet material, a gauge mounted upon said shaft, and screw-threaded means carried by said shaft for adjusting the position 20 of said gauge longitudinally of said shaft for side registering purposes, said means being held against axial movement relative to said shaft but being free to rotate relative thereto. 25

Signed at Chicago, Illinois, this 12th day of August, 1921.

JOSEPH R. BLAINE.
